UNITED STATES PATENT OFFICE

STEPHEN D. HARTOG, OF ST. LOUIS, MISSOURI, ASSIGNOR TO HARRY J. HATER, OF CINCINNATI, OHIO

PISTON

Application filed December 18, 1928. Serial No. 326,832.

My invention relates to improvements in pistons, and more particularly to pistons adapted for use in internal combustion engines.

5 Better results are obtained from internal combustion engines having light weight reciprocating parts, such as the pistons, and the light weight metals usually utilized for this purpose are aluminum, aluminum alloy, 10 magnesium and similar metals. These metals have properties which must be considered in the formation of pistons, namely, a relatively low specific gravity, a relatively high thermal conductivity, and a comparatively high 15 thermal expansion ratio. It is the object of this invention to produce a piston using these metals, in which the latter property is rendered comparatively ineffective for all practical purposes.

20 An important object of this invention, therefore, is the production of a piston so constructed that the heat of combustion, which causes undesirable expansion of the piston skirt is so diverted and impeded in 25 the course of its transmission from the head of the piston to its skirt, that its influence upon the skirt of the piston is reduced to a minimum.

Another object of my invention is to produce a piston, both thrust faces of which will be in constant contact with the surface of the cylinder walls.

A further object of my invention is to control expansion of the piston so that it 35 will work efficiently at all operating temperatures.

Other objects and advantages of my invention will be apparent during the course of the following description.

40 In the accompanying drawings which form a part of this specification and wherein like characters of reference denote like or corresponding parts throughout the same,

Figure 1 is a front elevation of my improved piston,

Figure 2 is a side elevation thereof,

Figure 3 is a vertical central sectional view on the line 3-3 of Figure 1,

Figure 4 is a transverse sectional view 50 taken on the line 4-4 of Figure 2, and

looking in the direction of the arrows, and, Figure 5 is a bottom plan view of the piston.

In the drawings, wherein for the purpose of illustration is shown a preferred embodiment of my invention, the numeral 10 designates the head of the piston having a depending rim 11 provided with a series of ring grooves 12 to receive suitable packing rings, not shown. The skirt 13 of the piston is 55 separated from the head 10 and rim 11 by a circumferentially extending opening 14. The piston skirt is relieved by being completely cutaway at diametrically opposite points, and said cutaway portions 15 extend from points spaced from the bottom of the skirt to the opening 14. A rib or strut 16 is arranged centrally of each cutaway portion and connects the head or rim 11 of the piston 60 with the portion of the skirt forming the lower side of the cutaway portion 15. The struts 16 are offset inwardly to avoid contact with the cylinder walls, and are formed integrally with the head and skirt of the piston. 65

Piston pin receiving hubs or bosses 17 are integrally formed on the struts 16 adjacent their centers, and are provided with the usual bores 18. These hubs preferably extend inwardly beyond the struts 16, and while they may also extend outwardly beyond the struts, they must clear the cylinder walls. Transverse struts 19 connect the hubs 17 adjacent their inner ends, with the skirt 13 at the side edges of the cutaway portions 15. The struts 19 are arranged horizontally and function to resist the side thrust to which the piston is subjected when in operation. 75

Reinforcing ribs 19' are arranged interiorly of the struts 19, on the upper and lower 80 edges thereof, and increase in width from the boss 18 to the piston skirt, as shown in Figures 4 and 5.

It will be seen, then, that the hubs 17 are joined at their outer ends to the head and the lower portion of the skirt by the substantially vertically extending struts 16, and joined at their inner ends to the skirt by the transverse struts 19, which are arranged substantially horizontal. At a suitable position 85 90 95 100

between the struts 16 and 19 there is an opening 20 dividing the inner end of each hub from the outer end thereof, and said opening 20 may be cut after the piston is cast, but is 5 preferably cast with the piston. The hubs 17 are consequently separated by the opening 20 into spaced inner and outer portions, the inner portions being integrally connected with the struts 19 and the outer portion of the hubs 10 17 being integrally connected with the struts 16 there being no direct connection between the struts 16 and the struts 19, or between the separated portions of the hubs. The struts 16 and 19 are, therefore, independent 15 of one another, and heat passing from the head 10 through the struts 16 will not be conducted to the struts 19 and the adjoining skirt portions.

The non-thrust side of the piston skirt is 20 provided with an inclined slit 21 which extends in a generally vertical direction from the bottom of the skirt to the opening 14 which separates the head from the skirt, and the thrust side of the skirt is unbroken. A 25 substantially continuous annular bearing surface is, therefore, formed adjacent the bottom of the skirt and is unbroken except for the single slit 21 which is slightly inclined from the vertical. While the slit 21 completely 30 separates the non-thrust side of the skirt, the arrangement of the transverse struts 19 and the portions of the skirt below the openings 15 which are braced by the struts 16, is sufficient to hold the separated parts of 35 the non-thrust side of the skirt in position.

The arrangement of the strengthening ribs 19' gives the necessary rigidity to the separated portions of the skirt.

In the operation of my improved piston, 40 the head portion is subjected to direct heat generated by the explosion of gases in the combustion chamber, and this heat is conducted away through the integrally connected struts 16 and through the surrounding 45 metal of the cylinder. The struts 16 are the only portions of the piston having direct or integral connection with the head of the piston and the only path by which the heat may be conducted to the piston skirt. The heat 50 is so reduced when it reaches the bottom of the skirt that very little is transmitted upwardly to the side walls of the skirt, and is, therefore, comparatively ineffective due to the long and circuitous route which it must 55 travel.

It will be noted that this construction results in the inner bosses operating at a lower temperature than the outer bosses, as they are 60 separated from the head and receive heat from the head only through the struts 16 and the lower portions of the skirt.

The slit 21 is for the purpose of allowing 65 for expansion, but does not materially weaken the skirt because of the arrangement of the transverse ribbed struts 19 and the sub-

stantially continuous annular bearing surface at the bottom of the skirt, said arrangement effectively bracing the split portion of the skirt.

Referring to Figure 5 it will be seen that 70 the under side of the piston head is provided with three spaced, substantially parallel ribs 22. These ribs extend down the inner sides of the piston head to a point adjacent the hub 18, and consequently strengthen the rib 16, as 75 seen in Figure 3, as well as the head of the piston, and provide for balanced heat dissipation.

This invention is an improvement on the piston covered by my pending application 80 No. 227,705 filed October 21, 1927.

While I have shown and described the preferred embodiment of my invention it is to be understood that various changes in the size, shape and arrangement of parts may 85 be resorted to without departing from the spirit of my invention or the scope of the subjoined claims.

Having thus described my invention, what I claim and desire to protect by Letters Patent is:

1. A piston comprising a head, skirt and piston pin hubs, each of said hubs comprising spaced portions, one of said spaced portions of each hub being connected to the head 95 and the lower portion of the skirt, and the other portion of each hub being connected to the sides of the skirt, said skirt being separated by a slit inclined from the vertical on the non-thrust side thereof. 100

2. A piston comprising a head, skirt and piston pin hubs, said hubs being split whereby they are divided into spaced portions, one of said portions of each hub being joined by a member with the head and skirt and 105 the other portion of each of said hubs being joined by a member with the sides of said skirt, said skirt being separated on its non-thrust side by a substantially vertical extending slit, the separated portions of the 110 skirt being braced by the joining members.

3. A piston comprising a head, skirt and piston pin hubs, members joining said hubs with the head and skirt, and members joining said hubs with the side portions of the 115 skirt, said hubs being split between the joining members whereby said joining members are independent of one another, and said skirt being separated on its non-thrust side by an inclined slit, the separated portions of the skirt being braced by the joining members. 120

4. A piston comprising a head, a skirt spaced from said head by a circumferentially extending opening, said skirt being provided with diametrically opposed cutaway portions, longitudinal struts connecting the head with the portions of the skirt at the lower ends of the cutaway portions and arranged adjacent the centers of the cutaway portions, 125 130

piston pin hubs carried by said struts and projecting inwardly therefrom, a transverse strut connecting the inner end of each hub with the skirt adjacent the side edges of the 5 cutaway portions, said hubs being split between the longitudinal and transverse struts whereby the hubs are each divided into spaced portions, one portion connected to the longitudinal strut and the other portion connected 10 to the transverse strut, said skirt having an inclined slit extending from the bottom thereof to the circumferential opening dividing the head from the skirt.

5. A piston comprising a head, a skirt 15 spaced from the head and provided with diametrically opposed cutaway portions extending from the top of the skirt to a point spaced from the bottom thereof, whereby a substantially continuous annular bearing 20 surface is provided adjacent the bottom of the skirt, a longitudinal strut extending across the center of each cutaway portion and integrally connecting the head with the portion of the skirt arranged at the bottom of 25 the cutaway portion, said strut having a piston pin hub integrally formed therewith and extending inwardly therefrom, a transverse strut integrally connecting the inner end of each piston pin hub with the portions of the 30 skirt adjacent the side edges of the cutaway portions, the hubs being split between the longitudinal and transverse struts whereby the struts are each divided into spaced portions, the outer portion being connected to the 35 longitudinal strut and the inner portion being connected to the transverse strut, the skirt being provided on its non-thrust side with an inclined slit extending from the bottom of the skirt to the space between the head 40 and skirt, the separated portions of the skirt being braced by the portions of the skirt below the cutaway portions, and by the longitudinal and transverse struts.

6. A piston comprising a head, skirt and 45 piston pin hubs, members joining said head and skirt, and members joining said hubs with the side portions of the skirt, said last mentioned members having reinforcing ribs extending from a point adjacent the hubs to 50 the piston skirt, said hubs being split between the joining members whereby said joining members are independent of one another, and said skirt being separated on its non-thrust side by an inclined slit, the separated portions of the skirt being braced by 55 the joining members and strengthening ribs.

7. A piston comprising a head, skirt and piston pin hubs, struts joining said hubs with the head and skirt, struts joining said hubs 60 with the side portions of the skirt, and reinforcing ribs on said last-mentioned struts, said ribs increasing in width from the hubs to the piston skirt, and said hubs being split between the joining struts, whereby said 65 struts are independent of one another.

8. A piston comprising a head, a skirt separated from said head, piston pin hubs, members joining said hubs with the head and skirt, and members joining said hubs with the side portions of the skirt, said hubs being 70 split between the joining members whereby said joining members are independent of one another, and said skirt being separated on its non-thrust side by an inclined slit, the separated portions of the skirt being braced and 75 held in position by the last named joining members.

9. A piston comprising a head, a skirt spaced from said head, piston pin hubs, struts joining said hubs with the head and skirt, 80 and struts joining the hubs with the side portions of the skirt, said hubs being split between the struts whereby said struts are independent of one another and the first named struts are the only connection between the 85 head and skirt, and said skirt being separated on its non-thrust side by an inclined slit, the separated portions of the skirt being braced and held in position by the last named struts.

In testimony whereof I affix my signature. 90
